UNITED STATES PATENT OFFICE.

WALTER S. HAVEN, OF RACINE, WISCONSIN.

FLUID-HEATING SYSTEM.

Application filed February 16, 1920, Serial No. 358,811. Renewed January 31, 1925.

To all whom it may concern:

Be it known that I, WALTER S. HAVEN, a citizen of the United States of America, and resident of Racine, Racine County, State of Wisconsin, have invented certain new and useful Improvements in and Relating to Fluid-Heating Systems, of which the following is a specification.

This invention relates to certain improvements in fluid heating apparatus; and the objects and nature of the invention will be readily understood by those skilled in the art in the light of the following explanation of the accompanying drawings illustrating what I now believe to be the preferred embodiment or mechanical expression of my invention from among other forms, constructions, arrangements, and combinations within the spirit and scope thereof.

An object of the invention is to provide improved means in (so-called) vacuum fluid heating systems whereby a partial vacuum is maintained in the radiator system by the vacuum creating action of a body of liquid descending in a closed conduit and repeatedly used to reduce waste of the liquid.

A further object of the invention is to provide a fluid heating system in which a partial vacuum pull is exerted upon the radiators by a column of liquid descending through a series of closed chambers arranged at different elevations the liquid periodically filling and being drained from one chamber to the next lower one by positive gravity action.

A further object of the invention is to provide improved valve mechanism for a closed chamber in communication with the radiators of a fluid heating system, whereby the chamber will be periodically filled and emptied with a liquid, to create a pressure reducing and air expelling action in the chamber which will cause a partial vacuum pull upon said radiators.

A further object of the invention is to provide an improved drainage system wherein liquid is successively drained from one closed chamber to another to successively fill said chambers for expelling air therefrom and then to successively drain said chambers to produce a partial vacuum acting upon the radiators of a fluid heating system.

A further object of the invention is to provide improved means for automatically

and periodically filling and draining a tank by improved float valve mechanism.

A further object of the invention is to provide a fluid heating system having liquid actuated means for maintaining a partial vacuum in the radiators, with improved automatic means for stopping and starting the liquid supply to the vacuum creating means at predetermined pressures in the radiators, above and below atmospheric pressure for example.

A further object of the invention is to provide an improved pressure regulator comprising means for automatically opening or closing a valve controlling the pressure creating means, according to predetermined variations in the pressure.

A further object of the invention is to provide a fluid heating system arranged for a partial vacuum pull through the radiators of the system, wherein as the steam is shut off from a radiator, the vacuum pull is also shut off therefrom.

A further object of the invention is to provide certain improvements in combinations of parts, and features of construction and arrangement as more fully and particularly set forth hereinafter, with the end in view of producing a highly efficient and advantageous fluid heating system.

Referring to the accompanying drawings:

Fig. 1 is a diagrammatic illustration of my improved steam heating system.

Fig. 2 is a detail vertical section through one of the drainage tanks showing valve mechanism which may be employed therein.

Fig. 3 is a detail vertical section through the pressure regulating mechanism for automatically controlling the liquid supply.

Fig. 4 is a detail elevation of a radiator illustrating means that might be employed for closing the pipe at the discharge end of the radiator as the steam pipe at the opposite end of the radiator is closed.

Fig. 5, is a detail vertical section illustrating means for closing a radiator from the air pipe line.

Portions of the radiators of the radiator system of a steam or vapor heating system are shown at 1, these radiators being merely diagrammatically illustrated to indicate any preferred heat radiators connected with a steam generator in such manner that a

partial vacuum created in said radiators is communicated to said generator to draw steam or other hot fluid therefrom into the radiators and to expel dead air from the radiators in advance of the hot vapor or other heating medium.

The radiators are shown as each provided at one end with a steam pipe 2, which pipes are in communication through any suitable 10 pipe line with a steam generator not shown. At the opposite end of each radiator is provided an air pipe 3 to receive the air from the radiators and through which a partial vacuum pull may be maintained through 15 the radiators, these air pipes communicating with a suitable pipe line 4, diagrammatically illustrated.

The steam pipes 2 and the air pipes 3 are provided with suitable cut-off valves 5 20 and 6 respectively, and mechanism which will be hereinafter more fully described, is preferably provided whereby closing of the steam pipe cut-off valve of a radiator, will automatically close the air pipe cut off valve 25 of said radiator for preventing unnecessary vacuum pull through the radiator when it is not in use and thereby reduce leakage into the air pipe by cutting off dead radiators.

30 The air pipes of the radiators may also be provided with any suitable arrangement of check valves to prevent back flow of air into the radiators, and with thermostatic valves to prevent outflow of steam from the 35 radiators, and the pipe line to which said air pipes connect is provided with a final air discharge to atmosphere equipped with means to prevent back flow of air.

Between the radiators and said final air 40 discharge to atmosphere, the air pipe line is provided with means for producing a partial vacuum in said line and the radiators, comprising a series of tanks, compartments or other chambers to be successively filled 45 with liquid to force air from such chambers to the next lower one, and to be successively drained from one to the other, under such conditions as to create a partial vacuum therein and thereby exert air exhausting pull 50 through the series of tanks and the air pipe line on the radiators.

In the particular example illustrated, I 55 show a vertical series composed of any suitable number of elevated closed tanks, chambers or compartments 7, 8, 9, 10, arranged in different horizontal planes, so that liquid will flow from the highest tank 7 to the next tank 8 below, and so on down from tank to tank throughout the series, so that 60 each tank will be successively filled and emptied.

A pipe 11 extends through this series of tanks from the top of tank 7 to the bottom of tank 10, and above tank 7 it is suitably 65 connected to a pipe 12 of the air pipe line.

The pipe 12 is in open communication with pipe 11 for free flow of air from the pipe line into the tanks by way of pipe 11, but is closed against back flow from pipe 11 to the air line by a check valve 13 in pipe 11 70 above the uppermost tank.

Any suitable means may be provided for supplying water or other liquid to the series of tanks for carrying on the partial vacuum producing action resulting from the successive filling and emptying of the tanks. For this purpose, I show a water supply pipe 14, from any suitable source of water under pressure (such as a municipal water supply system) from which water is supplied for maintaining a normally approximately constant flow of water into the uppermost tank 7. A suitable valve 15 is provided in pipe 14 for automatically shutting off and controlling the rate of flow of water into the tank system through this pipe as will be hereinafter fully explained.

The pipe 11 extending through the tank series is arranged below the lowermost tank, for the discharge of air and liquid 90 from the series of tanks, as shown at 17. This discharge to atmosphere preferably constitutes the final air discharge or outlet to atmosphere for the entire air line from the radiators, and also forms a water discharge to atmosphere. This outlet to atmosphere is provided with any suitable means to prevent admission of air to the drain pipe, shown in the present instance, as a liquid seal 18 through the medium of which the air and water in the drain pipe are discharged to atmosphere, the water overflow from the liquid seal passing to any suitable drain or offtake (not shown). The pipe 11 adjacent its outlet end is preferably 100 provided with a freely downwardly opening check valve 19, to prevent upflow of water from the liquid seal under conditions that might possible arise.

In the example illustrated, as thus far described, the air line from the radiators includes pipes 11 and 12, as well as the series of tanks, as the air flows therethrough on its way from the radiators to the final discharge to atmosphere at liquid seal 18.

Each of the tanks of the series is provided with suitable means to prevent drainage of liquid from the tank while the tank is being filled and the air is being expelled therefrom, and to start the operation of draining the liquid from the tank into the next lower tank or into the water seal 18, when the tank has been filled with liquid, and by this draining or emptying process to create a partial vacuum in pipe 12. The means I prefer to employ to close the drainage outlet from each tank when the liquid has been drawn therefrom, and to open the drainage outlet and start the downflow of liquid from the tank when the latter has been filled are auto- 115 120 125 130 135

matic in action. Each tank will thus be periodically automatically filled and then emptied, the liquid passing down successively from tank to tank, and each tank as it is filled discharging air into the next lower tank, until the air is finally discharged to the atmosphere through liquid seal 18, and each tank as it is emptied drawing air from the next upper tank until the uppermost tank is reached, which latter draws the air from the air pipe line and the radiators to create a partial vacuum therein.

In the present exemplification of mechanism for performing these operations, I show each of the tanks as provided with an approximately central transverse partition 20 dividing the tank into two superimposed closed chambers 21, 22. The pipe 11 where it passes through this partition is provided with a suitable closure plug 23 forming non-communicating sections 11^a and 11^b of this pipe in chambers 21 and 22, respectively. The pipe section 11^a is in open communication with chamber 21 adjacent the top and bottom of said chamber, for instance, through the medium of perforations 24 and 25 at its upper and lower ends, respectively.

The pipe section 11^b is in communication at its upper end with chamber 22, through suitable perforations 27 in said pipe section. An additional drain from chamber 22 to pipe 11 is also provided by means of a pipe 28 extending from the bottom of the tank into pipe 11 at a point in said pipe below the tank. This drainage pipe is provided with a suitable float-controlled valve for opening or closing the drain, as will be hereinafter more fully described.

In order to prevent excessive noise, due to the air and water flowing in the pipe when the system is in operation, a muffler is preferably provided for pipe 11^a, shown in the present instance, as a pipe 29 surrounding pipe 11^a in spaced relation and extending the full height of chamber 21. This pipe is in communication with chamber 21 through suitable perforations 30 and 31 at its base and upper end respectively. The connection between the water supply pipe 14 and the uppermost tank of the series, is exemplified as provided by a pipe 32 extending into upper chamber 21 of the uppermost tank from pipe 14 downward nearly to the bottom of said chamber. A suitable shut-off valve 33 is preferably provided in said pipe.

The float-controlled valve for the drain pipe 28 leading from the bottom of chamber 22, is shown as comprising a valve head 34 adapted to close down upon a valve seat formed at the port in the bottom of the compartment which leads into pipe 28. This valve seat is shown as a tapered valve seat 35. The valve 34 is adapted to close down on the seat to prevent flow from compartment 22 sometime before compartment 21

begins to overflow into compartment 22, and is adapted to rise from the seat and permit the flow from compartment 22 after compartment 21 has nearly completely emptied into compartment 22, and for this purpose the valve is shown as controlled by a float 36 in compartment 21.

Exemplifying this arrangement, the valve may be provided with an upwardly extending stem or valve rod 37 extending through partition 20 into compartment 21. The valve rod is preferably surrounded by a guide pipe 38 extending from the upper part of compartment 21 to any desired depth into compartment 22, and said guide pipe may be provided with air vents, shown as perforations 39, just below the partition 20.

An operating connection is provided between the float 36 in compartment 21 and the valve rod 37, which connection may comprise a lever 40 secured to the float and fulcrumed in a suitable bracket 41, and having a link connection 42 with said valve rod, the parts being so arranged that lifting of the float will seat valve 34 and dropping of the float will raise the valve from its seat.

The float is of such size or lifting power, that it will lift and seat valve 34 when the liquid in compartment 21 reaches the level of the float, and the float is preferably arranged adjacent the bottom of compartment 21 so that a comparatively small amount of liquid in said compartment will lift the float. For this purpose the float is shown as a hollow ball of less specific gravity than water, but of sufficient weight to drop by gravity and thus open valve 34 when the water in compartment 21 falls below the float. If desired, air escape and overflow means from compartment 21 to the lower compartment may be provided in addition to guide pipe 38, such an additional means being provided by an overflow pipe 43 having its open upper end arranged in the upper part of compartment 21 of the tank, and its lower discharge end arranged adjacent the bottom of compartment 22 of the tank.

In operation, the upper compartment of a tank is first filled, in the case of the uppermost tank, through pipe 32 from the water supply, and in the case of one of the lower tanks through the perforations 24 and 25 in pipe 11^a which forms a continuation of the drain 11^b of the next upper tank. As the water rises in the compartment, float 36 is soon reached, thus closing valve 34 and preparing compartment 22 to hold water. The air in compartment 21 is driven ahead of the water rising in the compartment and is thereby forced therefrom into compartment 22, through guide pipe 38 and overflow pipe 43, and when compartment 21 is nearly filled and the water therein reaches the level of the upper ends of said guide pipe and overflow pipe, the water will overflow

through the guide pipe and overflow pipe into the lower compartment to fill the latter and drive the accumulated air therefrom through the perforations 27 in pipe 11^b and thence into the next lower tank and ultimately to the atmosphere.

As the overflow from compartment 21 fills compartment 22, means are provided for ultimately opening the upper compartment directly into the lower, so that the accumulated liquid in the upper compartment will rush into the lower, approximately completely fill the latter and drive all of the air therefrom through pipe 11^b.

For this purpose, a port is provided in partition 20 for the flow of liquid from the upper to the lower compartment, and this port is surrounded by a preferably tapered valve seat 44. The flow of liquid through this port from compartment 21 is controlled by a suitable valve shown as a tapering valve 45, adapted to close down on the valve seat to prevent flow into compartment 22 from compartment 21 through this port when compartment 21 and afterwards compartment 22, are filling, and adapted to rise from the seat and permit the flow after compartment 21 is filled, and compartment 22 has been nearly filled, to rapidly complete the filling of the lower compartment from the upper.

As a means for accomplishing this result, the valve 45, if so desired, can be provided with a depending stem or valve rod 46 extending into compartment 22, to the lower end of which is pivoted a rod 47, as shown at 48, one end of said rod being pivoted through the medium of a suitable bracket to the wall of the tank as at 49, and the other end of the rod having a float 50 fixed thereto, the float being of such specific gravity and the parts being so arranged and positioned in the lower compartment of the tank, that when said compartment is nearly filled with water, the float will be raised by the liquid to open valve 45 and permit free flow from the upper compartment into the lower, and when the water has been discharged from the lower compartment to such an extent that its level is below the float, the latter will drop, and close valve 45, thus preparing the upper compartment for refilling.

By the mechanism as thus far described, it will be seen that the upper compartment of a tank is first filled, the lower compartment at the same time being made ready to hold water by the automatic closing of the valve in drain 28, and the air in the upper compartment will be forced into the lower. When the upper compartment is filled it will overflow into the lower and as the latter is filled the air therein will be forced out through pipe 11^b into the next lower tank and finally to the atmosphere. The complete filling of the lower compartment is ac-

complished by the opening of valve 45 to permit the water in the upper compartment to rush rapidly into the lower compartment to fill the same, and by the rapid downrush of water to draw air therewith from the upper compartment and also draw air into said compartment from pipes 11^a, 12 will cause air to be drawn into the same through openings 24 and 31, from the next upper tank of the series or from the air pipe line. The final draining of the lower compartment to form a vacuum in the latter, is accomplished by the automatic opening of drain 28 at the bottom of said lower compartment. Thus it will be seen that the upper and lower compartments of each tank are arranged to successively fill and drain, thus successively creating a vacuum in the upper and lower compartments to exert an air exhausting pull upon the next upper tank and finally upon pipes 12 and 4 and the radiators of the system. At the same time the liquid in the tanks is successively drained into the next lower tank to repeat the vacuum creating operation therein, and the air in the tanks is successively forced into the next lower tank until the air and liquid are finally discharged to atmosphere at the lower end of pipe 11.

During the normal operation of the apparatus, the valve 33 is open and water is constantly flowing into compartment 21 through pipe 32, except when pressure in the air pipe line closes the water supply through valve 15 and its pressure actuated controlling means. The water supply to pipe 32 is cut off so long as the pressure in the air pipe line 3, 4, 12 is sufficient to actuate the lever 58 against its adjustable weight to close valve 57. When the valve 57 is closed, whatever water previously delivered to the tanks 7, 8 etc. and remaining therein travels down through the same if sufficient in volume to operate the valves, functioning as herein described, and is finally discharged at 17. The rate of flow of water through pipe 32, into compartment 21 is controlled by valve 33. The flow through pipe 32 is relatively slow with respect to the rapid outflow through the discharge controlled by valve 45. The valve 33 is set to cause the compartment 21 to fill in a predetermined length of time, say for instance, every ten minutes more or less, whereas the compartment is emptied very rapidly say in fifteen or twenty seconds, when the valve 45 is raised. The down flowing water passing through the single pipes 11 joining the tanks 7, 8, etc. drags or sucks the air from above and acts as a check valve in preventing back flow of air from a lower tank to an upper tank. The air is carried down with the water through these single pipes but the air cannot flow upwardly in said pipes against the descending water, hence I do not find it necessary

to use check valves in the pipe connections between said tanks; that is between check valves 18 and 19.

With the parts in the positions shown by Fig. 2, the upper compartment has been emptied and is refilling but the water has not yet reached the level necessary to close the discharge valve 34 of the lower compartment 22. The lower compartment 22 is discharging and the rapid downflow of water pipe 11 (from branch 28) is drawing air through pipe 11^b, perforations 23, chamber 22 (above the water level) and from compartment 21 (above the water level) through perforations 39 and pipe 38. By the time compartment 22 is empty, the slowly rising water in compartment 21 will raise float 36 and close discharge valve 34, and continue to force air from the upper into the lower compartment. The air is discharged from the lower compartment of the bottom tank 10, through the discharge 17 of pipe 11, (bubbling up through the water seal) by the action of the water flowing into and discharging from said compartment, as described in connection with the illustration Fig. 2.

When the valve 34 of said lower compartment of the bottom tank is closed, the water overflowing into said compartment from the upper compartment of said tank, forces air from said lower compartment through perforations 23, pipe 11^b, 11 and discharge 17 and this air discharge continues until the water in the lower compartment reaches and elevates float 50 and discharge valve 45 and thereafter continues even if the water in the lower compartment overflows through perforations 23 as air is thereby carried down pipes 11^b, 11, with the water. When the water level in the upper compartment drops sufficiently, the discharge valve 34 is opened, and the outrush of water through branch 28 and pipe 11, sucks out, entrains and carries air which is discharged at 17.

The same body of water is thus used over and over again to successively produce air exhausting operations, thereby effecting economy in the use of municipal water, and at the same time an exceedingly efficient air exhausting system for heating plants is produced.

The air exhausting means as thus described, is adapted for use when the steam pressure in the radiators is less than atmospheric pressure and it is necessary to provide means for drawing air from the radiators. When, however, the radiator system is under pressure above that of the atmosphere, there is no necessity of providing air exhausting means for the radiators as there is then no air leakage into the radiator system and the dead air will be forced into the air pipe line. I therefore, provide means in my improved system, for automatically discontinuing the

filling and draining of the tanks to produce air exhausting suction, when the pressure in the radiator system is such as to make unnecessary the employment of such suction, thus avoiding a great waste of water. 70

For this purpose, I preferably automatically cut off the flow of water through pipe 14 into the uppermost tank of the series, when pressure above atmospheric exists in the radiator system and in pipe 12. In the example illustrated, I provide the valve 15, in pipe 14, this valve being shown as comprising a casing having an inlet 55 from the source of liquid supply through pipe 14, and an outlet 56 communicating with the lower end of pipe 14 which leads to the supply pipe of the uppermost tank. 75

The outlet 56 forms a valve seat, shown as a tapering seat, on which a valve head 57 is arranged to be seated to stop the flow of water through said valve. The valve is operated by a lever, which is in turn actuated, to start or stop the flow of water, by suitable pressure operated means connected with the radiator system. For instance, a lever 58 is provided, extending outwardly from the valve casing through a lateral extension 59, and pivotally connected at its inner end to the valve stem 60 of valve head 57 as shown at 61. The lever is shown as pivoted intermediate of its ends in the valve casing, as by providing a flexible rubber cork 62, plugging the end of extension 59 so as to provide a leak proof connection for the valve casing, the cork being pierced by the lever 58 and forming the fulcrum therefor. 90

The means for actuating lever 58 to start or stop the flow through valve 15, is shown as a flexible diaphragm 64, having a rod 65 fixed thereto and pivotally joined to lever 58 adjacent its outer end. 95

The diaphragm forms the flexible wall of a pressure chamber 66 connected by air pipe 67, to the radiator system, preferably through air line pipe 12. The extreme outer end of lever 58 is preferably provided with a counter weight 68 which may be adjustably positioned along the lever, to cause diaphragm 64 to elevate and close valve 15, and stop the flow of water to tank 7, when any predetermined pressure in the radiator system is reached. In practice, the counter weight is usually adjusted to cause closing of valve 15 and the shutting off of the flow of water to the tanks, as soon as pressure in the radiator system rises above atmospheric pressure, and to cause the flow of water to the tanks to start again as soon as the pressure drops below atmospheric. 110

The system as above described being in operation, air exhausting pull is exerted on pipe line 4, and on all of the radiators of the system when the air outlet valves 6 of the latter and the air exhausting means are 115 120 125 130

in operation. When, however, as in mild weather, it is desirable to put out of use certain of the radiators, it becomes necessary in the interest of economy and efficiency, to prevent the air exhausting action as above described upon the radiators which are not in use; since an even greater amount of energy would be expended in maintaining a vacuum in these radiators not in use, than would be expended if the latter were working. It is therefore essential to efficient operation of the system, that when the steam to any radiator is shut off, that the air valve 6 of said radiator also be closed, so that the air exhausting mechanism will not act upon the radiators not in use, but only upon the radiators in active use.

It will be found, however, that through carelessness, or neglect, the valve 6 will often be left open after valve 5 of a radiator has been closed, thereby continuing the air exhausting action upon said radiator and putting unnecessary work upon the vacuum creating means. I therefore have provided means for automatically closing the air outlet valve 6 of a radiator whenever the steam inlet valve 5 thereof is closed, and for re-opening valve 6 as soon as valve 5 is re-opened.

Any preferred mechanical means may be employed for causing this coaction between valves 5 and 6. In the present example, I have shown simple and efficient means wherein the valve 6 comprises a casing having a lateral extension 70 forming the connection between the radiators and the valve casing, the air pipes 3 leading to the air pipe line 4, being connected to the ends of said casing.

A valve head 71 is provided in extension 70, arranged to seat therein to form a closure between the radiator and the air pipe line. The valve head may be actuated by a lever 72, to open or close said valve, the lever being shown as extending through the valve casing and pivoted therein, a suitable air tight joint 73 being provided at said pivot. Lever 72 is arranged to be operated so as to unseat valve head 71 and open valve 6, whenever valve 5 is opened. When valve 5 includes a usual rotating valve stem 74, this may be accomplished by a flexible connection shown as a cable 75, wound around valve stem 74 at one end and connected to lever 72 at its opposite end, and so arranged that opening movement of valve 5 will wind the cable upon valve stem 74, and pull lever 72 so as to open valve 6. When valve 5 is rotated in the opposite direction so as to close the same, and the pull of cable 75 upon lever 72 is released, the lever may be moved in the opposite direction so as to close valve 6, by a suitable spring 76.

The cable 75 preferably extends through the radiator and may be enclosed in a pro-

tective casing 77 shown as extending from valve 5 to lever 72, to protect the cable from the effects of the heat of the radiator.

Claim is not made herein to the provision of cut-off valves for the outlets of the radiators to assure closing and opening of the radiator outlets when the radiator inlets are closed and opened, as such improvement is disclosed and claimed by my application filed June 17, 1925, Serial No. 37828 for fluid heating apparatus or system.

It is evident that various changes, modifications and variations might be resorted to without departing from the spirit and scope of my invention and hence I do not wish to limit myself to the exact disclosure hereof, but consider myself entitled to all such variations and departures as involve the definitions of the following claims.

What I claim is:—

1. Apparatus for maintaining negative pressure in advance of the heating fluid in fluid house heating systems comprising a closed liquid drainage passage, means for supplying liquid thereto, and means for automatically forming bodies of water at successive points along said passage and causing them to descend in succession therein so as to draw the air in said passage downwardly through the same behind said descending bodies of water to exert air exhausting action throughout the said passage, substantially as described.

2. In a fluid house heating system, apparatus for maintaining a vacuum in the system in front of the heating fluid therein, comprising a series of successive closed liquid chambers at different levels, means whereby air exhausting columns of liquid are caused to successively descend from chamber to chamber and drive the air in said chambers successively downward from chamber to chamber, and means for supplying liquid to the top chamber of the series.

3. Apparatus for exhausting dead air from fluid house heating systems comprising a drain pipe, and means for forming the same body of liquid into columns of liquid to successively descend through said pipe, substantially as described.

4. Apparatus for maintaining negative pressure in the radiator systems of fluid heating plants, characterized by a series of chambers having air exhausting connections with each other and with the radiator system, a source of liquid supply, and a series of devices constructed and arranged for successively and automatically filling and draining liquid from said chambers for successively forcing air from and drawing air into said chambers, substantially as described.

5. In a fluid house heating system, in combination, radiators, and means for maintaining negative pressure pull on the radiators,

said means comprising a series of closed chambers at different levels each having an offtake and an inlet, the inlet of the uppermost chamber being connected with said radiators, the offtake of the lowermost chamber leading to the atmosphere, and the inlet of each of the chambers below the uppermost chamber being connected with the offtake of the next upper chamber to exert minus pressure pull through said chambers upon said radiators, and connections for supplying water to the uppermost chamber and for successively filling and emptying said chambers into the next lower one and finally to the atmosphere through said inlet and offtake, substantially as described.

6. Apparatus for maintaining minus pressure pull in a fluid heating system, comprising an air line having an air discharge to atmosphere, said air line including a vertical series of closed chambers each having an outlet communicating with the next lower chamber and finally with the atmosphere, means for supplying liquid for filling the uppermost chamber of said series, and for successively draining the liquid from said uppermost chamber through said outlet and successively filling and emptying the chambers below and finally discharging the water from the lowermost chamber at said outlet to atmosphere.

7. In combination, an upper water compartment, a lower water compartment, a source of water supply for the upper compartment, an overflow connection for discharge of water from the upper part of the upper compartment into the lower compartment, a drainage discharge from the upper compartment to the lower compartment, a valve controlling said discharge, means controlled by the water level in the lower compartment for opening and closing said valve, an offtake from the upper part of the lower compartment, a drainage discharge from the lower compartment, and means for opening and closing said last named discharge controlled by the water in the upper compartment.

8. Apparatus for exerting negative pressure pull on the heating fluid in house heating systems, comprising a series of liquid tanks at different levels, means to supply a charge of liquid to the upper tank, and air exhausting connections from each tank to the next upper tank and finally to the heating system forming drainage outlets from each tank to the next lower tank and finally to the atmosphere, said outlets being provided with automatic valve mechanism whereby the outlet is closed after the tank is drained and commences to refill, and is automatically opened after the tank is filled and has partially emptied to complete the drainage of said tank.

9. A tank arranged to be automatically

successively filled and drained, an upper and lower compartment, an air vent from the upper portion of said upper compartment to said lower compartment, said vent serving as an overflow from the upper to the lower compartment, a bottom discharge from the upper to the lower compartment, a valve for opening and closing said discharge provided with buoyant means in said lower compartment for unseating said valve when the overflow from the upper compartment has partially filled said lower compartment, and means for draining said lower compartment.

10. A tank arranged to be automatically successively filled and drained, comprising upper and lower compartments, an overflow from said upper to said lower compartment, a discharge port from said upper to said lower compartment, a valve for automatically opening said port when the overflow from the upper compartment has partially filled the lower compartment, a drainage pipe from said lower compartment, and a valve for automatically closing said drainage pipe as the upper compartment is being filled, and for opening said drainage pipe when said upper compartment has drained into the lower compartment.

11. Apparatus for exerting negative pressure pull on the heating fluid of a heating system, comprising a series of tanks at different levels each having an upper and lower compartment, means for supplying liquid to the upper compartment of the uppermost tank, a drain pipe from each of said lower compartments to the upper compartment of the next lower tank and finally to the atmosphere, and means in each tank for automatically draining the upper compartment into the lower compartment when the overflow from the upper compartment has partially filled the lower compartment.

12. Apparatus for exerting negative pressure pull on the heating fluid of a heating system, comprising a series of tanks at different levels, each having an upper and a lower compartment, means for supplying liquid to the upper compartment of the uppermost tank, an overflow from the upper to the lower compartment of each tank, an overflow from each lower compartment to the upper compartment of the next lower tank and finally to the atmosphere, means in each tank for automatically draining the upper compartment into the lower compartment when the overflow from the former has partially filled the latter, and means for draining each lower compartment into said overflow leading to the upper compartment of the next lower tank when said upper compartment has drained into said lower compartment.

13. Air exhausting means comprising a vertically elongated closed combined air ex-

hausting and liquid drainage passage having a top liquid supply and a top check valve-controlled suction inlet, and having a final bottom check-valve controlled air and liquid discharge, and means for causing the liquid entering said passage at the top to form into successive air compressing and air exhausting bodies in working by gravity down through the passage by stages to said discharge, said passage being internally formed to provide down flowing streams of liquid to prevent back flow of air.

14. Air exhausting means comprising a

series of tanks at different levels connected by combined air and liquid pipes to form a closed combined air exhausting and liquid drainage passage, the top tank having a water supply inlet and an inlet through which air exhausting pull or suction is to be maintained by the action of the water passing down through the passage conduit, each pipe arranged for the downward passage of both air and liquid from tank to tank, the bottom tank having a combined air and liquid discharge to atmosphere.
